UNITED STATES PATENT OFFICE

159,160

COMBINED FRAME, POWER LIFT ATTACHMENT, AND TRACTOR HOOD

George W. Mork, South Milwaukee, Wis., assignor to Bucyrus-Erie Company, South Milwaukee, Wis., a corporation of Delaware

Application June 10, 1948, Serial No. 146,891

Term of patent 14 years

(Cl. D14—3)

To all whom it may concern:

Be it known that I, George W. Mork, a citizen of the United States, residing at South Milwaukee, county of Milwaukee, State of Wisconsin, have invented a new, original, and ornamental Design for a Combined Frame, Power Lift Attachment, and Tractor Hood, of which the following is a specification, reference being had to the accompanying drawing, forming part thereof.

In the drawing:

Figure 1 is a side elevational view of my combined frame, power lift attachment, and tractor hood, showing the power lift attachment in lowered position.

Figure 2 is a side elevational view of my combined frame, power lift attachment, and tractor hood, showing the power lift attachment in raised position.

Figure 3 is a top plan view of the combined frame, power lift attachment, and tractor hood, with the power lift attachment in lowered position.

Figure 4 is a front elevational view of the combined frame, power lift attachment, and tractor hood, with the power lift attachment in raised position.

Figure 5 is a rear elevational view of the frame, with the power lift attachment partly cut away.

Figure 6 is a top front perspective of my combined frame, power lift attachment, and tractor hood, showing the power lift attachment in lowered position.

The side of the combined frame, power lift attachment, and tractor hood opposite that shown in Figures 1 and 2 presents substantially the same appearance as that depicted.

The dotted lines shown in the figures to indicate the outline of the crawler tracks of the tractor are for illustrative purposes only.

I claim:

The ornamental design for a combined frame, power lift attachment, and tractor hood, as shown and described.

GEORGE W. MORK.
